UNITED STATES PATENT OFFICE.

TERESA DENNEY, OF BROOKLYN, NEW YORK, ADMINISTRATRIX OF
HARMER DENNEY, DECEASED.

MACHINERY FOR MAKING TUBES OF PAPER.

SPECIFICATION forming part of Letters Patent No. 692,636, dated February 4, 1902.

Application filed July 21, 1899. Renewed June 14, 1901. Serial No. 64,600. (No model.)

To all whom it may concern:

Be it known that HARMER DENNEY, deceased, late of the borough of Brooklyn, in the city and State of New York, and a citizen of the United States, was during his lifetime the inventor of certain new and useful Improvements in Machinery for Making Tubes of Paper, &c., and that I, TERESA DENNEY, a citizen of the United States, and a resident of 10 and whose post-office address is No. 250 Emerson Place, in the borough of Brooklyn aforesaid, having been duly constituted and appointed administratrix of the estate of the said HARMER DENNEY, deceased, as set forth in 15 the accompanying petition, do hereby declare that the following is a full, clear, and exact description of the said invention, reference being had to the accompanying drawings, making a part of this specification, in which—

20 Figure 1 is a plan view of an apparatus constructed according to the said invention. Fig. 2 is a side view of a part of the said apparatus. Fig. 3 comprises (in brackets) a plan and side view of a spring which forms part 25 of the mechanism illustrated in Fig. 2, but cannot be conveniently shown in the latter. Fig. 4 is a front elevation, on a larger scale, of a part of the apparatus shown in plan in Fig. 1. Fig. 5 is a longitudinal sectional view in 30 the line $v v$ of Fig. 6 of certain parts also shown in elevation in Fig. 4. Fig. 6 is an end view viewed from the dotted line $l l$ of Fig. 4. Fig. 7 is a sectional view as viewed from the left and taken in the line $x x$ of Fig. 4. Fig. 8 is a front elevation, on a larger scale, 35 of parts of the apparatus not shown in Fig. 4, but illustrated in plan in Fig. 1. Fig. 9 is an end view, as viewed from the left, of the portion of the apparatus illustrated in Fig. 4. Fig. 10 is a plan view of parts not shown 40 in Fig. 9, but situated at the right of the parts shown in said Fig. 9. Fig. 11 is a detail plan view of a portion of the apparatus not so specifically shown in Fig. 1, and Fig. 45 12 is a vertical sectional view taken in the line $y y$ of Fig. 11.

Supported in suitable bearings a is a revolvable hollow sleeve A , which may be revolved by a band-wheel a' or other suitable means 50 and which has fast upon it a spur-wheel b . Extended from the end of this sleeve is a

forked support c , which provides bearings for a reel or revolvable carrier B , which when the machine is in operation carries the roll of paper d or like material in ribbon form, 55 from which, as herein presently explained, the inner layer of the tube is to be formed. Fast axially at one of its ends to the inner end of the sleeve is a mandrel C , upon which the material is wound in the production of the 60 tube and the diameter of which determines the internal diameter of the finished tube. This mandrel is made detachable from the sleeve in order that mandrels of different diameters may be used according as tubes of 65 different internal diameters are to be made. Arranged in due relation with the opposite end of the mandrel to sever the tube at a point beyond said end is the cutting-off mechanism by which, as hereinafter explained, the 70 continuous tube is severed into sections of the lengths desired. The mandrel being fast to the sleeve, as explained, it necessarily rotates therewith.

The ribbon d' of paper, from the reel B 75 passes lengthwise through the sleeve and makes its exit from one side of the interior thereof to and upon the adjacent part of the mandrel. A spring v' is arranged to press upon the ribbon as it passes to the sleeve in 80 order to hold the ribbon under proper tension.

Supported in a fixed annular bearing e , suitably alined with the sleeve, is a revolvable annular head A' , which has at one side and fast to it an annular spur-gear f . By means 85 of a spur-pinion e' this spur-gear f connects with a spur-wheel f' on a counter-shaft g , which, supported in suitable bearings, is below and parallel with the sleeve. At its opposite end this counter-shaft connects by a 90 spur-wheel g' and pinion f'' with the spur-wheel b of the sleeve, so that the spur-gear f is driven from the rotation of the sleeve. The mandrel passes through central opening a' of the head, as more fully illustrated in 95 Fig. 5. At opposite sides of the opening a' the head carries two revolvable feed-rolls b' , one upon each side of the mandrel. These rolls are adjusted by means of screws h^5 and are circumferentially grooved, as illustrated 100 in Fig. 6, on semicircular curves corresponding to the diametrical size of the mandrel,

their office being to feed the ribbon d' to and along the latter, said rolls being rotated in the proper direction by motion-transmitting devices hereinafter presently described. The 5 feed-rolls b^4 in addition to their feeding motion are revolved or carried bodily around the axis of motion of the mandrel and in the same direction with the rotating motion of the mandrel and the core carried thereon, 10 but with only about half the speed of the mandrel, the latter in its revolutions slipping within the core to an extent corresponding to the difference of its revolute speed as compared with that of the core. While, therefore, 15 the core formed upon the mandrel rotates more slowly than the mandrel, and consequently more slowly than the sleeve and the reel, it follows that the ribbon is wound upon the mandrel to an extent proportioned 20 to the excess of the speed of the sleeve and its mandrel over that of the core, which is retarded by the slower revolutions of the head with its feed-rolls. Meanwhile the slower motion of the head with its feed-rolls is sufficient 25 to insure the winding thereon of a further number of layers of paper, as hereinafter explained.

The feed-rolls, it will be observed, serve the double purpose of regulating the revolute speed of the core upon the mandrel and of feeding the core longitudinally along the latter.

The requisite motions are given to the feed-rolls by appropriate mechanism, which, as 30 shown in the drawings, is provided for operation as follows: Supported by and rotating within a fixed annular bearing h is a barrel or hollow cone B' , which has at one end a spur-gear h^2 , while its opposite end projects 35 into the space a^4 of the head A' and preferably works smoothly therein, as indicated in Fig. 5. This smaller end of the barrel has a spur-gear h^4 . Each feed-roll b^4 has at one end of its shaft a worm-wheel i .

40 The head A' is provided with bearings i^4 for short shafts k , each of which has at one end a worm k' , which gears with the adjacent worm-wheel i , while at its opposite end is a spur-pinion k^4 , which gears with the spur-gear h^4 . As the head A' and barrel B' rotate 45 at different rates of speed, the revolutions of the head carrying the spur-gear h^4 around the spur-gear h^2 of the barrel motion is transmitted through the worm-wheels and to the feed-rolls to feed the ribbon of material to 50 and along the mandrel, as hereinbefore described. As the ribbon d' passes from the sleeve to the barrel it is guided in its course to the mandrel by a sloping or curved block 55 j , carried by the sleeve and revolved therewith. The position of this guide j with reference to the mandrel is illustrated in Fig. 5. The barrel has an intermittent rotating movement in a direction the opposite of that of the head. This is provided as follows: A secondary shaft D , parallel with the axial line of 60 the mandrel, sleeve, head, and barrel, has a

spur-pinion l , which gears with the spur-gear h^2 of the barrel. On this shaft is a ratchet-wheel m . Pivoted on the same shaft is a swinging bar m' , at one end of which is a spring-pawl m^2 , which engages with the ratchet-wheel m . At the opposite end of this bar is an antifriction-roller m^4 , which receives the impact of a cam n on the shaft g , which, 70 as hereinbefore explained, is rotated through the spur-gears b and g' and pinion f' . Pivoted in a fixed bearing is a hand-lever n' , on which is an eccentric n^2 . Around this eccentric n^2 passes a strap on the end of a longitudinally-movable rod n^4 , the opposite end of which is pivotally connected with the arm of the swinging bar m' , this being preferably accomplished by a switch or vent in the end of the rod bearing against a pin n^5 on the bar 80 and pressed against the latter by a spiral spring u^7 . By manipulating the rod by means of the hand-lever and its eccentric the lower or impact end of the swinging bar m' may be moved more or less from the path of the cam n , so that the action of the cam upon the swinging bar may be varied in degree with a proportionate change in the extent and duration of the action of the pawl upon the ratchet-wheel, a proportionate change in the extent 90 of each impulse given to the rotation of the barrel, and a proportionate modification in the speed of the feed-rolls carried by the head. In the operations above described the ribbon d' is wound spirally upon the mandrel as the 100 sleeve rotates and the ribbon is fed thereto, the wound ribbon being moved along the mandrel as this feeding proceeds. This ribbon thus fed and wound upon the mandrel forms the core of the completed tube. 105

To complete the tube, it is essential that a further number of layers of paper or like material be wound around the core formed, as just described, by the ribbon d' . This is provided for as follows: Placed suitably adjacent 110 to the mandrel is a paste-box E , in which is provided a paste-feeding roller r , upon the shaft of which is a gear r' . Above this roller and geared therewith by a pinion r^4 is a paper-feeding roll s , and behind this latter are 115 reels F , proportioned in number to the number of strips of paper or the like to be wound upon the core, as just explained. In the drawings, Fig. 1, three strips are shown at u , and the apparatus is so arranged, as illustrated in said figure, that the strips in passing to the core on the mandrel are oblique to the latter, the degree of this obliqueness determining the pitch at which the strips are wound upon the core. The ends of the strips 120 are at the outset of the operation attached to the core, so that the strips are drawn to and wound upon the core as the latter revolves with the mandrel and is carried longitudinally along the same, as hereinbefore explained. As the strips pass over the paste-feeding roll their inner surfaces are coated with paste or adhesive material, so that when wound they adhere to the surfaces upon which 125

they are wound. From the oblique position of the strips with regard to the mandrel as they pass to the latter it follows that the strips reach the mandrel in, so to speak, "successive" order, so that while the first strip in order is pasted direct to the surface of the core the second strip in order is wound upon and pasted to the outer surface of the second after the latter has been wound upon the core and the third in like manner over and upon the second, so that the completed tube comprises, with the core and three strips, four plies of material pasted or cemented one upon another. In practice it is preferable that the paste-feeding roller *r* be provided with a scraping-roller *q* to regulate the thickness of the paste thereon in feeding the paste to the strips, and tension-bars *t* may be provided to regulate the tension of the strips as they pass from the reels to the paste-roller.

The paste-roller, the roller *s*, and the scraping-roller should be geared together, as shown at *H* in Fig. 11. To hasten the drying of the paste when the strips of material are wound upon the core, as described, a gas-burner *G* may be arranged in proper relation to the parts to dry the material as it passes along the mandrel, as described. As the tube thus produced may be continuous of a length to any degree proportioned to the length of the ribbon and the strips of material fed thereto, it is desirable that it be automatically cut into such lengths as may be desired for commercial or other uses. To provide for this, the invention includes the mechanisms shown more in detail in Figs. 8, 9, and 10 of the drawings.

Mounted in bearings upon a suitable frame at that end of the apparatus remote from the sleeve and its adjuncts is a shaft *I*, which carries a circular saw *K* and has a pulley *I'*, through which from any suitable source motion may be transmitted to the saw *K*. This shaft is capable of a longitudinal movement in its bearings and is connected, as presently explained, with the upper end of a lever *K'*, the lower end of which works in connection with a cam *K⁴* on a counter-shaft *K⁷*, which latter is driven through a pulley *L* from any suitable operating power. The speed and proportions of the cam *K⁴* should be such that when the cam actuates the shaft *I* to move the saw, as herein presently to be explained, the saw will move at substantially the same speed and in the same direction that the tube moves along the mandrel. When, as presently explained, the saw is released after cutting the tube, it is retracted to its original position by a spiral spring *M*, acting upon its shaft.

Extended beyond the saw, as shown in Figs. 1, 8, and 10, and supported in suitable guides or bearings are two parallel rods or bars *R* and *R'*. On the bar *R* is a stop or shoulder *a⁷* and at another portion of its length a clutch *b⁷*, which connects with the upper end of a lever *c⁷*, the lower end of which has a stud

d⁷. Upon the back of the cam is a stud *e⁷*. When the longitudinal movement of the bar *R* operates the lever *c⁷* to bring the stud *d⁷* in the path of the stud *e⁷*, the movement of the cam is stopped. The pulley *L*, it may be mentioned, has a frictional hold upon its shaft, so adjusted that when the cam is free the pulley end rotates the latter; but when the cam is stopped by the stud *d⁷* of the lever the friction is overcome and the pulley runs free without rotating its shaft. This is the condition when the saw is not in operation, and the bar *R* is retracted to produce this result by a spring *S⁷*, applied thereto, as indicated in Fig. 8. Upon the bar *R'* is provided a lever *T*, which at one end has a contact-plate *T'*, which is in the path of the tube as it passes off from the end of the mandrel. The opposite end of this lever is arranged to come in contact with the stop *a⁷* of the bar *R* when the end of the tube in passing off, as described, strikes the contact-plate and swings the lever *T*. This latter then slides the bar *R* to operate the lever *c⁷* to bring its stud *d⁷* away from the cam *K⁴*, which latter is then rotated and actuating the saw through the lever *K'* carries the latter along at the same speed as the tube. It is now necessary that the tube and saw be brought into such relation with each other that the saw will pass transversely through the tube to sever a section therefrom. To provide for this, the end of the tube which has passed from the mandrel is supported in a trough *N*, which is carried on a frame which is pivoted at its back, as shown at *N'* in Fig. 9. From this frame extends an arm *N⁷*, the free end of which rests upon a cam *t⁷* (shown in dotted outline in Fig. 9) upon the shaft *K⁷* of the cam. This cam *t⁷* lifts the end portion of the tube against the saw, and the latter being simultaneously carried along in the direction of the length of the tube the end portion of the latter is cut squarely off in a plane at right angles to the length of the tube.

What is claimed as the invention of the said HARMER DENNEY, deceased, is—

1. The combination with a mandrel and of a revoluble hollow head concentric with the mandrel, and feed-rolls carried by the hollow head, and arranged to feed the core along the mandrel, of a barrel concentric with the mandrel, revoluble at a speed different from that of the head, and mechanism for transmitting motion from the barrel to the feed-rolls to control the speed of the latter by changes in the speed of the barrel, substantially as herein set forth.

2. The combination with a revoluble tubular sleeve, a mandrel revoluble with the said sleeve, means for supplying a ribbon of material through the sleeve to the mandrel, a hollow head concentric with the mandrel, feed-rolls carried by the hollow head and arranged to feed along the mandrel the core formed thereon by the ribbon, a barrel concentric with the mandrel revoluble at a speed different from that of the head, and mechan-

ism for transmitting motion from the barrel to the feed-rolls, whereby the speed of the feed-rolls and consequently the pitch of ribbon wound on the mandrel may be changed 5 by changing the motion of the barrel, substantially as herein set forth.

3. The combination with a mandrel of a revoluble hollow head concentric with the mandrel and feed-rolls carried by the head 10 and arranged to feed the core along the mandrel, of a barrel concentric with the mandrel revoluble at a speed different from that of the head, mechanism for transmitting motion from the barrel to the feed-rolls, a shaft 15 geared to rotate in unison with the mandrel, means for transmitting a continuous rotary motion from said shaft to the head, and mechanism for transmitting an intermittent rotary movement from the shaft to the barrel in a 20 direction opposite to that of the motion of the head, substantially as herein set forth.

4. The combination with a tubular revolu-

ble sleeve, a mandrel revoluble with the said sleeve, means for supplying a ribbon of material through the sleeve to the mandrel, a 25 head concentric with the mandrel and revoluble in the same direction as the mandrel, and feed-rolls carried by the head for feeding along the mandrel the core formed thereon by the ribbon, of a barrel through which 30 the mandrel is passed, mechanism for actuating the feed-rolls from the barrel, means for adjusting the distance apart of the feed-rolls, a counter-shaft actuated from the tubular sleeve, and mechanism for transmitting 35 motion from the counter-shaft to the head and the barrel in opposite directions, substantially as herein set forth.

TERESA DENNEY,
Administratrix of the estate of Harmer Denney, deceased.
